United States Patent Office.

M. T. HITCHCOCK, OF SPRINGFIELD, MASSACHUSETTS.

Letters Patent No. 80,411, dated July 28, 1868.

IMPROVEMENT IN RAILROAD-CAR VENTILATORS.

The Schedule referred to in these Letters Patent and making part of the same.

TO ALL WHOM IT MAY CONCERN:

Be it known that I, M. T. HITCHCOCK, of Springfield, in the county of Hampden, and Commonwealth of Massachusetts, have invented a new and improved Car-Ventilator; and I do hereby declare that the following is a full, clear, and exact description thereof, reference being had to the annexed drawings, making a part of this specification, and to the letters of reference marked thereon, in which—

Figure 1 is a side elevation of said ventilator, shown as applied to the floor of a railway-car.

Figure 2 is a longitudinal vertical section, through fig. 1, and

Figure 3 is a horizontal longitudinal section, through line $x y$, fig. 1.

The main purpose of my invention consists in withdrawing the air from a railway-car, and such withdrawal and ejection of air I conceive to be best performed from the floor or lowest part of the car, although the apparatus will operate efficiently in other positions than that represented in the drawings, as is hereafter explained.

The ventilator consists of a T-shaped exhaust-tube, supplied with valves, and enclosed in a shell or case, which case is rigidly fastened to the floor of the car, the ends opening towards the respective ends of the car.

The upper end of the vertical portion of the T-shaped exhaust-tube passes through the floor of the car, and is opened or closed, like an ordinary furnace-flue, by a register set in the car-floor.

The ends of the horizontal portion of the exhaust-tube are not planes, but are formed by two planes intersecting the cylinders at an angle, as shown in the drawings, and these ends are provided with hinged valves, which are arranged to move freely under the pressure of a current of air, and are in such a relative position that when the valves at one end of the exhaust-tube are closed by a current, those at the opposite end will be opened, and therefore the exhaust will operate equally well in whichever direction the car is moving, without attention or adjustment from any quarter.

The shell or case which encloses the exhaust-tube is nearly semi-cylindrical, and is provided with flaring flanges or deflectors at each end, and two posts, against which the valves strike when opened. In actual use these posts will be covered with rubber, or other soft substance, and the ends of the tubes, against which the valves strike when closed, will be provided with a washer or cushion of the same, so that the valves will operate noiselessly in opening and closing.

The exhaust-tube and case are made cylindrical in form, for convenience and cheapness in manufacture, but may be prismatic or polygonal in cross-section, with no material difference in the efficiency of the apparatus.

The construction of my invention is as follows: The T-shaped exhaust-tube is formed of the horizontal cylinder B, and the vertical cylinder A opening into it, both being of the same or nearly the same diameter or internal capacity.

The ends of B are not circles, but are formed by the intersection of two planes, as $d e f$, meeting in the line of the vertical diameter of B, which line determines the position of the hinges $h h$. If, however, the apparatus be attached to the side instead of the bottom of a car, the line of the hinges $h h$ will still be in the vertical diameter of B, but will then be at a right angle to the axis A.

The angular ends of B are made precisely similar, so as to secure the same action, whether the car is moving in one direction or the other. The angle at which the planes which form the ends of B converge, is nearly a right angle, by which inclination I conceive the best effect of the valves to be produced.

To attach the valves to the cylinder B, a hinge-post, $g y$, is attached to the outer points of each end. The shape of each of the similar valves, $a b b$, is such as to cover one-half of the end of B, at whatever angle the cylinder is cut by the converging planes, and hinge-loops $h h$ are formed upon the straight edges of the valves, through which the hinge-post $g y$ passes, and about which the valves turn. In the drawings the vertical tube A is shown as entering a chamber, D', of enlarged capacity, so as to compensate for the air-space taken up by the bars or grate-work of the register R, in the floor of the car.

The shell or case is formed of an oval hood and a plane top, which is applied directly to the bottom of the car, or to a support extending below and parallel with the bottom, and there firmly secured. The edges of the

plane top project beyond the hood, so as to form flanges, by which the ventilator is fastened to the car. The vertical tube A is rigidly attached to the plane top of the hood, at the point where it enters it, and in ventilators of large size, the tube B may be further secured to the hood by stays, if necessary.

The exhaust-tube, valves, and shell, I prefer to construct of firm and smooth sheet metal, which affords even surfaces for the guidance of the currents, and I attach the ventilator nearly in the middle of the length of the car, or so that the register will open into the aisle.

I propose to apply to each car one or more of these ventilators, nearly in line with one another, the number necessary, to be determined by the size and use of the car.

The same ventilator may be applied with great efficiency to the roof of a car, or to the side of the "deck" of a double-roofed car, but I prefer to exhaust the air from the floor, a supply of fresh and pure air being introduced at the upper part by the use of the induction-ventilator, for which I have received Letters Patent, No. 74,534, and dated February 18, 1868, or by other devices for the same purpose.

The operation of my invention is as follows: The ventilator, being rigidly attached to the floor of the car, it is evident that when the car is in motion, in a direction opposite to the direction of the arrows, the air will enter the shell, somewhat condensed by the effect of the flaring flange c', and will rush through the shell, and around the sides of the exhaust-tube B.

The force of this entering current will be sufficient to close the valves b at the entering end, and the inclination of the valves so closed will deflect the air towards the space between the shell and the tube B. This current will move on past the other end of the exhaust-tube, and, by the well-known action of a moving current, will tend to draw the air in the exhaust-tube along with it, and the valves a will open to allow its passage.

The flange c, on the shell, will tend to cause a slight rarefaction of the current moving within the shell at that point, and thus increase its force and velocity. The curved red lines show the movement of the currents of air passing down through the register, and out of the exhaust-tube.

It is also evident that the more rapidly the car moves, the more powerful will be the exhaustion of air through the exhaust-tube B, and also that if the motion of the car should be reversed, the valves a will immediately close, while the valves b will open, and the eduction of air from the car will be the same in one case as in the other.

Some of the advantages of my invention are, its cheapness, simplicity, and the fact of its being entirely self-operating. It is also light, compact, and when applied to the bottom of a car, is entirely out of the way, and in great measure removed from sight. Its nature also enables me to place the ventilator between the ground and the bottom of the car, where the most favorable action of an eduction-ventilator can be obtained, as I believe that the system of creating a circulation of air in a railway-car, by withdrawing the air from the bottom of the car by means of the apparatus herein described, or by any other, the functions of which are the same, possesses many and great advantages over the system of car-ventilation now in use, and is new and novel as a means of thorough and self-operating ventilation.

I am aware that rotating ventilators have been constructed, in which the exhaust-tube was surrounded by a case or shell, so placed as to leave an air-passage between the shell and the exhaust-tube, and I do not claim such a construction as my invention, when considered apart from my described construction and arrangement of the several parts which constitute my improved ventilator.

Having described my invention, what I claim as new therein, and desire to secure by Letters Patent, is—

1. The T-shaped exhaust-tube, having inclined ends, and valves a b attached thereto, for the purpose of adjusting the action of the ventilator to the direction of the motion of the car, and enclosed within the shell C, which is rigidly attached to the car, in such a manner as to form an air-passage between the exhaust-tube and shell, the whole constructed, arranged, and operating substantially as set forth.

2. An exhausting-ventilator, rigidly attached to the bottom of a railway-car, and so arranged as to exhaust equally well, whether said car moves in one direction or the other, substantially as set forth, and to discharge the air from the car directly beneath the same, as specified.

In witness whereof, I have hereunto set my hand, this seventeenth day of April, A. D. 1868.

M. T. HITCHCOCK.
